Primary Examiner — Nathaniel D. Buckner

(57) **CLAIM**

The ornamental design for a connecting plug for a fiber optic cable end, as shown and described.

DESCRIPTION

1.1 is a perspective view of a connecting plug for a fiber optic cable end;

1.2 is a left side view thereof;

1.3 is a right side view thereof;

1.4 is a top plan view thereof;

1.5 is a bottom plan view thereof; and

1.6 is a front elevation view thereof.

The broken line showing in the reproduction is for the purpose of illustrating portions of the connecting plug for a fiber optic cable end, and forms no part of the claimed design.

1 Claim, 6 Drawing Sheets
